[57] CLAIM

The ornamental design for a combined comb and spray atomizer, as shown and described.

DESCRIPTION

FIG. 1 is a perspective view of a combined comb and spray atomizer, showing my new design;
FIG. 2 is a left side elevational view thereof;
FIG. 3 is a rear elevational view thereof;
FIG. 4 is a bottom plan view thereof; and
FIG. 5 is a perspective view of a combined comb and spray atomizer showing a modified form of my new design.
